BOMB RELEASE MECHANISM

Werner Buchal and Hermann E. Veit, Parkville, Md., assignors to The Glenn L. Martin Company, Middle River, Md., a corporation of Maryland

Application April 30, 1943, Serial No. 485,125

4 Claims. (Cl. 89—1.5)

This invention relates to an improvement in a bomb rack release unit and more particularly, a safety device on the bomb release lever of the control unit of a bomb rack.

In the conventional bomb rack, supporting a bomb shackle, there is a control unit having actuating levers which engage the release and arming levers of a bomb shackle. It is sometimes necessary and desirable to dump all of the bomb load before landing an airplane. When this occurs, the plane may be in a damaged condition and the ordinary means, such as the conventional bomb release, located in the bombardier's station and the emergency release mechanism may be out of operation. Under such conditions, it is necessary to enter the bomb bay and manually release the bomb shackle levers to release the bombs. The conventional bomb release mechanism makes the manual release of the bombs a very difficult operation. Several expedients have been employed to overcome the difficulty, but the result has usually impaired the efficiency of the bomb release mechanism or detracted from the safety of the device.

By this invention a safety device may be employed in connection with the bomb release unit lever whereby the manual operation may be easily accomplished.

The structure of the safety device of this invention may be readily applied to existing installations with a minimum of rework.

Further and other objects will become apparent from the description of the accompanying drawings which form a part of this disclosure and in which like numerals refer to like parts.

In the drawings:

Figure 1 is a perspective view of a bomb in a conventional bomb rack.

Figures 2 to 6 show one embodiment of the safety device for use on the bomb release unit.

Figures 7 to 12 show a modification of the invention.

Figure 1 of the drawings shows a bomb 1 supported by a bomb shackle 2 suspended from hooks 3 and 4 on upright members 5 and 6 which are integral with the structure of the airplane. On a cross bracket 7 is mounted the bomb shackle control unit 8. The bomb is supported from the bomb shackle by hooks 9 which engage the loops in straps 10. Lever 11 is the arming lever of the bomb shackle and lever 12 is the release lever. Levers 13 and 14 are mounted on the bomb shackle control unit and have outwardly extending flanges near the ends of the levers which surround the usual end of the bomb shackle levers

for the actuating thereof in response to the remote control of the bomb control unit. The release of the control lever units and the shackle levers will be explained in more detail. The control units are permanently mounted on the cross bracket between the upright portions of the bomb rack. The ends of levers 13 and 14 surround the ends of levers 11 and 12 when the bomb shackle is retained in place by hooks 3 and 4.

10 To release a bomb from such an arrangement, it is merely necessary to operate the control unit, first to rotate the control unit lever 13 in a clockwise direction which causes the rotation of shackle arming lever 11, and second, to cause the rotation of lever 14 in a counterclockwise direction to cause hooks 9 to disengage from the loops of bands 10 to release the bomb from the bomb shackle. The lever 14 has on the outer end a fixed projecting flange 15 and a hinged flange 16. 15 It will be noted when the lever 14 moves lever 12, the load is taken by the fixed flange 15. The purpose of the hinged flange 16 is to permit the manual release of the bomb by pivoting flange 16 out of the way and moving release lever 12 by 20 hand in a counterclockwise direction.

Figures 2 to 6 show one form of terminal end for lever 14. In these figures is shown lever 14 having a fixed flange 15 and the hinged flange 16. Flange 16 has portions 17 through which extends 25 the hinge pin 18. Extending at right angles to portions 17, parallel to the hinge pin are locking members 19. Members 20 serve to support the hinged flange on lever 14. Spring 21 urges the hinged flange to a position parallel with flange 15 and spring 22 is under compression and tends 30 to move the hinge pin and hinged flange downward as viewed in Figure 6.

When the flanges are parallel or in the normal position shown in Figure 2, and it is desired to 35 move the hinge flange to the position shown in Figure 3, it will be noted from Figure 4, that portions 19 extend under members 20, thus preventing the hinge action of flange 16. In order to 40 hinge flange 16 on the pin 18, it is necessary to move the hinge flange to the position shown in Figure 3, it will be noted from Figure 4, that portions 19 extend under members 20, thus preventing the hinge action of flange 16. In order to 45 lift flange 16 until members 19 disengage members 20. Spring 22 tends to prevent this motion. Flange 16 may be hinged to the position shown in Figure 3 against the force of spring 21. It is readily apparent that two definite movements are 50 required against the force of two springs, first to unlock and then, to hinge flange 16 outwardly to move release lever 12 by hand.

In the modification shown in Figures 7 to 12, the movable flange consists of member 26 which 55 moves on hinge pin 27 supported between mem-

bers 28 of lever 14'. Locking member 29, shown in two views, Figures 7 and 8, is placed over member 26 with a sliding fit. End portion 30 of member 29 extends through the cut out portion of lever 14' between members 28, to effectively prevent hinge action of member 26. Member 29 is held in the normal locking position shown in Figure 10 by means of tension spring 31. Coil spring 32 on the hinge pin tends to keep the hinged flange parallel to the fixed flange 15.

From the description of parts, it follows that it is necessary to move member 29 outwardly from the lever, or upwardly as shown in Figures 10 to 12, until portion 30 is clear of the hole in 14', then, and only then, is it possible to hinge flange 26 as shown in Figure 11. The manual operation of the movable flange entails two motions against the force of two springs to move the flange to the position shown in Figure 11, after which lever 12 can be manually operated.

It should be apparent that a bomb release unit so equipped with the safety flange, above described, cannot be moved accidentally by a fouled bomb-hoisting cable, nor can it be vibrated to a position where the bomb shackle release lever will inadvertently release a bomb, yet it is a simple manual operation to release a bomb when necessary and desirable.

It is to be understood that certain changes, alterations, modifications and substitutions can be made without departing from the spirit and scope of the appended claims.

I claim as my invention:

1. In a bomb release device, a bomb shackle, a control unit therefor, said bomb shackle having arming and release levers, said control unit having actuating members surrounding said arming and release levers, means whereby a portion of said actuating member may be pivoted out of the way for manually operating said release lever to release the bomb, said means comprising a hinged projecting bar member secured to said

lever to normally prevent independent movement of said release lever, said hinged projecting member having elements associated therewith forming a locking device to maintain said bar member in the projecting position, said elements required to be disengaged before it is possible to move said projecting members about the hinge.

2. An actuating lever for the release lever of a bomb shackle comprising a lever member substantially co-extensive with said shackle release lever, a fixed flange on said lever member to engage and move said release lever, a hinged flange pivoted to said lever member, a locking means therefor to prevent inadvertent movement of said release lever, said locking member for said hinged flange requiring manipulation before the hinged flange can be moved for manual actuation of the release lever.

3. An actuating lever for the release lever of a bomb shackle comprising a lever member having two projecting flanges positioned on each side of the shackle release lever, one flange being rigidly secured to said lever member to engage and move said release lever, the other flange being hingedly secured to said lever member, a spring biased locking device for maintaining said flange in the projecting position whereby said locking device must be moved to permit hinging of said flange.

4. In a bomb release device, a bomb shackle, a control unit therefor, said bomb shackle having an arming lever and a release lever, said control unit having an actuating member surrounding each of said arming and said release levers to prevent inadvertent movement thereof, and a manually operable latched, hinged portion on said release lever actuating member whereby said release lever may be disengaged from said actuating member for the manual release of a bomb, after said hinged portion is unlatched and pivoted out of the path of said release lever.

WERNER BUCHAL.
HERMANN E. VEIT.
